John E. Davis, Sherman Oaks, Calif., assignor to Na Mac Products Corp., Los Angeles, Calif., a corporation of California

Application August 13, 1946, Serial No. 132,481

Term of patent 14 years

(Cl. D44—22)

To all whom it may concern:

Be it known that I, John E. Davis, a citizen of the United States, residing at Sherman Oaks, in the county of Los Angeles and State of California, have invented a new, original, and ornamental Design for a Condiment Container, of which the following is a specification, reference being had to the accompanying drawing, forming a part thereof.

Fig. 1 is a front elevational view of a condiment container embodying my new design;

Fig. 2 is a top plan view of a condiment container shown in Fig. 1;

Fig. 3 is a bottom plan view of the same; and

Fig. 4 is a side elevational view of the same.

I claim:

The ornamental design for a condiment container, as shown.

JOHN E. DAVIS.
